UNITED STATES PATENT OFFICE.

EVERARD RICHARD CALTHROP, OF LONDON, ENGLAND.

LIFTING AND LIKE SLING OR CRADLE.

1,177,927.

Specification of Letters Patent.

Patented Apr. 4, 1916.

Application filed January 26, 1916. Serial No. 74,427.

To all whom it may concern:

Be it known that I, EVERARD RICHARD CALTHROP, a subject of the King of Great Britain, residing at London, in the county 5 of Middlesex, England, have invented new and useful Improvements Relating to Lifting and like Slings or Cradles, of which the following is a specification.

My invention has reference to lifting and 10 like slings and cradles and has for its object to provide an improved sling or cradle whereby a person may be comfortably and securely slung in any desired position and to provide means for the rapid release of 15 the person from the sling when necessary.

More particularly the invention relates to devices for the aforesaid purpose adapted for the use of aviators of the kind wherein the ends of the straps encircling the wearer's 20 body are secured together by a releasing device upon the operation of which the ends of the straps are freed so that the aviator may detach himself from the sling or harness.

25 In order that my invention may be readily understood and carried into effect I will now proceed to describe the same fully for which purpose reference should be had to the accompanying drawings in which:

30 Figure 1 is a view of my improved sling or harness showing its application to a life saving parachute for aeroplanes or like aerial craft. Fig. 2 is an elevation and Fig. 3 a section on line $a-a$ of Fig. 2 of a device for instantaneously releasing the sling or harness so that the whole may be slipped off the wearer. Fig. 4 is an elevation of a 35 slightly modified form of releasing device. Fig. 5 illustrates a modification of the arrangement shown in Fig. 1 for connecting the sling or harness to the aeroplane.

40 Referring now to Fig. 1 my improved sling or safety harness comprises two preferably annular members 1 through which the arms of the wearer may be inserted. Said members are connected by two straps adapted to pass across the shoulders one of 45 said straps 2 being provided with adjusting means while to the other 3 is secured one end of a strap 4 which for convenience I will term the main suspension member whereby the sling as a whole is suspended from a rope 5 or the like. This main suspension strap is passed upward and—in 50 order to provide a differential movement thereby more evenly distributing the weight

of the wearer—over a roller 6 carried by the rope 5 or the like then downward through an eye or loop 7 to a belt 8 encircling the waist of the wearer. The strap 4 is then continued down and provided with a padded portion 9 adapted to pass between the legs of the wearer then up to the aforesaid belt 8 where it is attached to a common fastening device 10 the function of which will be hereinafter more particularly explained. Secured to the aforesaid annular members or arm rings 1 are two adjustable straps 11 adapted to pass across the breast of the wearer said straps being connected to the waist belt 8 by the aforesaid common fastening device 10. This fastening device is a somewhat important feature of my invention as its function is to hold the two ends of the waist belt the end of the main suspension member and the lower ends of the breast straps all securely in the locked or operative position while at the same time permitting by a single operation instantaneous release of the ends of the said straps so that the whole sling may be slipped off the wearer.

45 In Figs. 2 and 3 I have shown a suitable form of fastening device for this purpose. It comprises a plate 12 having means such as the slots 13 and 14 for engaging respectively one of the straps 11 and one end of the belt 8. Said plate 12 is provided with a centrally disposed journal on which is rotatably mounted the sleeve 16 having a 50 flange 17 provided with two downwardly projecting portions 18 which are adapted as will presently be explained to engage the members attached to the ends of the straps 4 and 11 and the end of the belt 8. An operating handle 19 is riveted or otherwise secured to the flange 17 and a nut 20 engaged with the threaded portion of the journal 15 thus rotatably connecting sleeve 16 flange 17 and handle 19 with the plate 12. A stop 55 100 21 is provided on the plate 12 to limit the movement of the handle 19. As above stated the part of the common retaining and releasing device so far described is connected to one of the straps 11 and to one end of the belt 8 and it is therefore necessary to provide means for connecting thereto the end of the other strap 11 the end of the strap 4 and the opposite end of the belt 8. To this end I provide the two plates 22 and 23 the plate 22 having slots 24 whereby the 60 105 110 end of the belt 8 and the end of the breast

strap 11 may be connected thereto while the plate 23 is formed with slots 25 for the attachment of the end of the strap 4. Each of the aforesaid plates 22, 23 is provided with a tongue 26 having an upstanding projection 27 (see Fig. 3) thereon adapted to be engaged by the projections 18 on the flange 17 when the handle 19 is in the position illustrated in Fig. 2.

10 In some cases I may find it desirable to dispense with the two straps 11 and connect the arm rings 1 by straps passing across the breast of the wearer as shown by the dotted lines in Fig. 1. Said straps being joined 15 in the center by a releasing device so that it may be released simultaneously with the release of the belt 8 and in Fig. 4 I have shown a device for effecting this. In this arrangement the plate 12 carries two releasing devices similar in construction to that described with reference to Figs. 2 and 3. 20 The two rotatable parts of said devices are actuated simultaneously by the lever 19 pivotally mounted at 27' on the plate 12 through the link 28 thereby disengaging the tongues 26 in a manner similar to that described with reference to Figs. 2 and 3. 25 Means are provided for preventing accidental displacement of the operating lever 19 shown in Figs. 1 and 4, such as for instance a sleeve of leather adapted to slide on the strap 11 and over the handle 19 to hold it 30 in place or a rubber band or the like may be employed for a similar purpose.

Instead of operating both releasing devices in the manner just described one of them may be provided with a handle 19 as 40 shown in Fig. 2 and a chain passed around the edges of the rotatable portions so that both will be rotated through the required angular distance to release the tongues 26 when the handle 19 is operated.

45 A sling in accordance with this invention may be employed for any purpose where it is desired to suspend a person safely with the facility of instantaneous release and I may provide an arrangement of 50 ropes or the like passing over pulleys in such a manner that the sling suspended therefrom may be moved horizontally and vertically such for instance over the whole area of the front of a building or of a cliff. 55 Furthermore a device under this invention may be employed as a safety sling or harness for persons engaged in mountaineering or for seamen when engaged in hazardous duties on board ship or for lowering persons down mines or wells for exploration or for other purposes.

Although I have in the foregoing description referred generally to the uses to which my invention may be applied it may 60 here be observed that one of its most im-

portant applications is with life saving parachutes employed in connection with aeroplanes or like aerial craft. When employed for this purpose the sling or harness worn by the aviator is connected to the center bolt of the parachute 34 through the rope 5 as shown in Fig. 1 and to the floor or framework of the fuselage through the straps 29 terminating in eyes 30 adapted to engage an appropriate locking device 31 75 on or below the seat. Said locking device may be operated by a rod or the like 32 actuated by a suitable lever 33 arranged within convenient reach of the aviator so that when for any reason he has to use the parachute 80 it is only necessary for him to actuate the lever 33 and jump overboard.

The releasing mechanism just described may also be employed for releasing the 85 parachute case when this latter is carried in any special position or cavity in the base of the fuselage so that it may fall into its proper position. This may be effected by providing a locking device 35 actuated by the rod 32 and handle 33 so that when said 90 handle is operated the harness worn by the pilot will be released and simultaneously the 95 parachute case freed.

In Fig. 5 I have illustrated a modified form of device for releasing the pilot from the aeroplane. In this construction the straps 29 at each side of the harness are attached by means of a stirrup piece 35' which is engaged by a lever 36 pivoted at 37 between two plates (one of which 38 only is 100 shown) and having a nose 39 thereon engaging said stirrup 35'. Attached to the lever 36 is the end of a Bowden wire mechanism 40. The plates 38 are attached by straps 41 and dog hooks 42 to an eye bolt 43 in 105 the floor or other convenient part of the aeroplane. The handle operating the Bowden release for the harness may also operate a Bowden release for the parachute so that it will be released simultaneously with 110 the release of the aviator. It is to be observed that in this aspect of my invention I have provided a sling which while normally holding the pilot securely to his seat and to the parachute rope will in no wise impede the movements of his arms and legs thereby enabling him to retain complete control of the machine while any desired amount of freedom of movement in his seat 115 may be secured by adjustment of the various straps to the extent required. A further advantage is that whatever position the machine is flown in either normally or upside down as when looping-the-loop the pilot is securely held to the seat and it is only necessary in case of emergency to actuate the releasing mechanism above referred to to effect instantaneous release of the sling 120 from the seat.

125 It is further to be observed that by the 130

provision of the common releasing device hereinbefore described the operation of a single lever instantaneously disconnects the straps composing the harness leaving the 5 aviator suspended by the arm rings 1 only, so that upon nearing the ground or encountering any obstacle such as a tree or the roof of a building the harness can be released and the aviator can easily slip one 10 arm after the other out of the rings 1 and grasp said rings with his hands so as to be unencumbered and thus enable him to effect a safe landing.

Claims.

- 15 1. A lifting sling or cradle comprising the combination with a pair of arm rings and a belt, of shoulder, breast, and main suspension straps, and a common releasing device so arranged that upon operation of said device said belt, breast, and main suspension straps will be so freed as to allow the sling or harness to be slipped off the wearer.
- 20 2. In a lifting sling or cradle, the combination of arm rings, shoulder straps, a breast strap, means for connecting one end of each of said straps to the arm rings, a main suspension strap, means for securing one end of said suspension strap to a shoulder strap, a belt, means for securing together the free ends of said belt and straps, and means operable by the wearer whereby said wearer may instantaneously release himself from said straps and belt.
- 25 3. In a lifting sling or cradle, the combination of arm rings, shoulder straps, means for connecting one end of each of said straps to the arm rings, a main suspension strap, looped above and passing down the back and between the legs of the wearer, means for securing one end of said suspension strap to a shoulder strap, a belt, means for securing together the free ends of said belt and straps, and means operable by the wearer whereby said wearer may instantaneously release himself from the sling.
- 30 4. In a lifting sling or cradle, the combination of arm rings, shoulder straps and breast straps connected at one end to said rings, a main suspension strap having one end secured to a shoulder strap, a belt, plates attached to the free ends of said straps and belt, and means operable by the wearer for enabling said ends to be connected together and instantaneously released.
- 35 5. In a lifting sling or cradle, the combination of arm rings, shoulder straps and a

breast strap connected at one end to said rings, a main suspension strap having one end secured to a shoulder strap, a belt, plates 60 secured to the free ends of said straps and belt, projections on said plates, and means operable by the wearer for coacting with said projections to secure the plates together, and permit of their instantaneous 65 disconnection to allow the wearer to release himself from the straps and belt.

6. In a lifting sling or cradle, the combination with a harness adapted to embrace the body of the wearer, of a plurality of 70 plates connected to the free ends of the elements of said harness, projections on the said plates, an angularly displaceable member, projections on said member and means operable by the wearer for enabling the projections on the angularly displaceable member to be engaged with or disengaged from the projections on the plates carried by the ends of the elements of the harness.

7. In a lifting sling or cradle, the combination with a harness comprising arm rings and straps and adapted to embrace the body of the wearer, of means operable by the wearer whereby said wearer may instantaneously release himself from said harness, 85 means whereby said harness may be detachably secured to an aeroplane or the like, a parachute secured to the harness and to the aeroplane, and means operable by the wearer for simultaneously releasing said harness 90 and parachute from the aeroplane.

8. In a lifting sling or cradle, the combination of a harness comprising arm rings and straps, a plurality of devices for securing said harness around the body of the wearer, 95 and a lever operable by the wearer whereby said wearer may actuate said devices and instantaneously release himself from the harness.

9. In a lifting sling or cradle, the combination of a harness comprising arm rings and straps, a plurality of devices for securing said harness around the body of the wearer, a lever operable by the wearer whereby said wearer may actuate said devices and instantaneously release himself from the harness, 100 means whereby said harness may be detachably secured to an aeroplane or the like, a parachute secured to the harness and to the aeroplane, and means operable by the pilot 110 for simultaneously releasing said harness and parachute from the aeroplane.

EVERARD RICHARD CALTHROP.
